UNITED STATES PATENT OFFICE.

GEORGE EDWARD WHITE, OF JOHANNESBURG, TRANSVAAL, SOUTH AFRICA.

PUMP OR PUMPING APPARATUS.

Application filed December 22, 1921. Serial No. 524,170.

To all whom it may concern:

Be it known that I, GEORGE EDWARD WHITE, a citizen of the United States of America, and resident of Johannesburg, 5 Transvaal Province, Union of South Africa, have invented certain new and useful Improvements in Pumps or Pumping Apparatus, of which the following is a specification.

This invention relates to pumps or pumping apparatus and has for its object to construct an efficient pump or pumping apparatus in a simple and inexpensive manner.

The invention comprises an arrangement 15 in which a plurality of suction pumps are employed co-operatively combined with a common suction pipe and a common delivery pipe and actuated by the same actuating means, and admitting of the efficient operation of the pumps with a comparatively short stroke.

The invention will be fully described in connection with the accompanying drawings wherein I illustrate a practical embodiment of the invention.

Fig. 1 is a part sectional elevation of the arrangement.

Fig. 2 is a sectional plan of Fig. 1 on line *x-x*.

Fig. 3 is a sectional plan of Fig. 1 on line *y-y* and

Fig. 4 is a sectional plan of Fig. 1 on line *z-z*.

In accordance with the invention I employ 35 a pipe or tubular casing 1 which constitutes a common suction pipe for the barrels 2, 3, of the two pumps shown.

The lower pump is positioned in the suction pipe 1 and is surrounded by the lower 40 portion 4 of the delivery pipe 5, and the upper pump is positioned in the delivery pipe 5 above the upper end of the suction pipe 1, communication being established between the suction pipe 1 and the underside 45 of the valve 6 of said upper pump. The driving means for the various pumps is located in the common delivery pipe 5.

Although I show the arrangement including two pumps and their co-operating parts, 50 it is to be understood that any desired number of pumps may be employed disposed one above the other and co-operating with each other as hereinafter explained.

The lower end of the upper pump barrel 55 2 is screwed into a part or casting 7 which is constructed to form a seating 8 for the

upper pump valve 6. 9 is a piece screwed into the casting 7 above the seating 8 which serves as a stop for the valve 6 in an upward direction and provides passages 10 60 for the water to pass through on the up-stroke of the bucket 11 or equivalent part of the pump, 12 being a suitable lifting valve provided in the bucket 11.

The casting 7 is constructed with a flange 65 13 which is screw-threaded exteriorly to receive the upper end of the common suction pipe 1. The casting 7—see Figs. 2 and 3—is constructed with a lateral passage 14 which communicates with the underside of the 70 valve 6 so that the water is free to pass from the interior of the common suction pipe 1 through said latter passage 14 and past the valve 6 into the barrel 2 on the up-stroke of the bucket 11. The liquid which enters the 75 pump barrel 2 on the up-stroke of the bucket 11 passes through the valve 12 on the down-stroke of the bucket 11 during which stroke the valve 6 is closed.

The upper end of the lower portion 4 of 80 the delivery pipe 5 is screwed into the casting 7 at 15, and the casting 7 is constructed to provide communication between the upper end of the lower portion 4 of the delivery pipe 5, and the portion of the delivery 85 pipe 5 above the casting 7.

A part similar to the casting 7, but without the flange 13, will be provided for each pump between the uppermost and lowermost pumps.

The lower end of the barrel 3 of the lowermost pump has screw-threaded connection with a casting 16 which is constructed to provide a seating 17 for a valve 18; 19 being the stop screwed into the casting 16 95 for the valve 18. The lower end of the lower portion 4 of the delivery pipe 5 has screw-threaded connection with the casting 16 at 20. The bucket or equivalent 21 of the lower pump is fitted with lifting valve 100 22 and operates on its up-stroke to draw the liquid from the common suction pipe 1 through the valve 18 into the barrel 3; the liquid passing through the valve 22 on the down-stroke of the bucket and the valve 18 remaining closed.

As shown in Fig. 4, the casting 16 may be constructed exteriorly with ribs 16^a which serve to maintain the casting 16 central of the suction pipe 1 whilst providing free passage for the liquid 110 up the suction pipe 1 to the uppermost and any intervening pumps.

The means for operating the pumps comprises a pump rod 23 which at its lower end is directly attached to the bucket 11 of the top pump, a yoke or cross-piece 24 attached 5 to the rod 23 above the top barrel 2, rods or long bolts 25, 26, which are attached at the upper ends to the yoke 24 and at the lower ends are attached to a yoke or cross-piece 27 fixed to the upper end of a rod 28 10 which at its lower end is directly attached to the bucket of the other and, as shown, lowermost pump.

As will be understood, when the pump rod 23 is lifted the pump buckets 11, 21, are 15 moved through the up-stroke and the water above them thereby raised up to the common delivery pipe 5.

The lower end of the suction pipe 1 is positioned in the well or sump from which 20 the liquid is to be pumped and, as shown, it is preferably fitted with a rose 29 in which is housed a plurality of valves 30; 31 being a grid fixed above and serving as a stop to limit the lift of the valves 30.

25 What I claim as my invention and desire to protect by Letters Patent is:—

1. Pumping apparatus comprising, in combination, a plurality of superimposed pumps, a common suction pipe, a common 30 delivery pipe enclosing all the barrels of said pumps, the delivery pipe being constructed in sections, and a part connecting the upper end of the suction pipe to the section of the delivery pipe of the uppermost 35 pump, said part also carrying the barrel

and the valve for the uppermost pump and providing a passage from the common suction pipe to the underside of the valve and a further passage between the adjacent sections of the delivery pipe. 40

2. Pumping apparatus comprising, in combination, a plurality of superimposed pumps, a common suction pipe, a common delivery pipe enclosing all the barrels of said pumps, the delivery pipe being constructed in sections, a part connecting the upper end of the suction pipe to the section of the delivery pipe of the uppermost pump, said part also carrying the barrel and the valve for the uppermost pump and providing a passage from the common suction pipe to the underside of the valve and a further 45 passage between the adjacent sections of the delivery pipe, and a common driving means for actuating all of said pumps, said driving means comprising a rod attached to the bucket of the uppermost pump, a yoke fixed to said rod, long bolts attached to said yoke, a further rod attached to the bucket of the other pump, and a further yoke fixed to 50 said last-mentioned rod, said further yoke being connected to the rod of the uppermost pump by the long bolts. 55

In testimony whereof I have signed my name to this specification in the presence of 60 two subscribing witnesses.

GEORGE EDWARD WHITE.
